United States Patent Office

Des. 195,298
Patented May 28, 1963

195,298

CHAIR ARM

Kenneth C. Kerr, 122 S. Riverside, Medford, Oreg.

Filed Dec. 12, 1961, Ser. No. 67,886

Term of patent 14 years

(Cl. D15—1)

Fig. 1

Fig. 2

Fig. 3

Fig. 4

Fig. 5

FIGURE 1 is an inner side elevation of a chair arm showing my new design;

FIGURE 2 is a bottom plan view of the said new design;

FIGURE 3 is a top plan view thereof;

FIGURE 4 is a foreshortened outer side elevational view of the present design taken on the line 4—4 of FIGURE 3; and

FIGURE 5 is a cross sectional view taken on the line 5—5 of FIGURE 3.

I claim:

The ornamental design for a chair arm, as shown.
